CLAIM

The ornamental design for a housing for an automatic vehicle locator, as shown and described.

DESCRIPTION

FIG. 1 is a left rear perspective view of the housing for an automatic vehicle locator comprising the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a right elevational view thereof; and,

FIG. 7 is a left elevational view thereof.
